MECHANISM TOWER FOR A BUNDLE TYING MACHINE

Douglas C. Mills, Adrian, Mich., assignor to
SOS Consolidated, Inc., Birmingham, Mich.

Filed Dec. 29, 1969, Ser. No. 20,655

Term of patent 14 years

Int. Cl. D15—05

U.S. Cl. D55—1

FIG. 2.

FIG. 3 -

FIG. 4 -

FIG. 5 -

FIG. 6 -

In the drawings:

FIG. 1 is a front quarter view in perspective of a mechanism tower for a bundle tying machine embodying my invention, environmental structure being shown in broken lines for illustrative purposes only;

FIG. 2 is a view in elevation taken from the right side of FIG. 1;

FIG. 3 is a plan view;

FIG. 4 is a view in elevation taken from the left side of the tower;

FIG. 5 is a front view in elevation; and

FIG. 6 is a rear view in elevation.

What I claim is:

The ornamental design for a mechanism tower for a bundle tying machine, as shown and described.
